UNITED STATES PATENT OFFICE.

OMER F. BARNES, OF ARCOLA, ILLINOIS.

GOLD-DREDGER.

SPECIFICATION forming part of Letters Patent No. 727,262, dated May 5, 1903.

Application filed July 22, 1902. Serial No. 116,537. (No model.)

To all whom it may concern:

Be it known that I, OMER F. BARNES, a citizen of the United States, and a resident of Arcola, in the county of Douglas and State of Illinois, have invented a new and Improved Gold-Dredger, of which the following is a full, clear, and exact description.

This invention relates to improvements in machines for use in dredging gold from water-beds or placer-mining. It is well known to placer-miners that the usual suction-dredgers are impractical or of little use in elevating gold from a river-bed or the like, because of the great specific gravity of gold as compared with sand and gravel—that is, while sand and water are lifted by the suction the gold will sink into the sand-bed to a depth too remote to be lifted or acted upon by the suction.

20 It is the object of my invention, therefore, to provide a simple means for collecting gold with the sand at a point so near the inlet of the suction-pipe that the gold will be elevated by the suction-draft.

25 I will describe a gold-dredger embodying my invention and then point out the novel features in the appended claims.

Reference is to be had to the accompanying drawings, forming a part of this specification, 30 in which similar characters of reference indicate corresponding parts in all the figures.

Figure 1 is a side elevation of a gold-dredger embodying my invention. Fig. 2 is a plan view of a form of collecting device that may 35 be employed, and Fig. 3 is a slight modification of the collecting device.

Referring to the drawings, 1 designates a crane or arm having a universal-joint connection 2 with a scow or float 3. A boom 4 40 depends from the crane and is vertically adjustable with relation thereto. The suction-pipe 5, extending from a suction-pump 6, has its lower end secured to the boom 4 by means of collars or clips 7.

45 Attached to the lower end of the boom is a collecting-plate 8, and the lower or inlet end of the suction-tube 5 is located a short distance above said plate and may be supported thereon by legs 9. The plane of the plate is 50 parallel with the end of the tube and extends in all directions therefrom. It will catch the

material coming from all directions. This plate 8 is provided with radial riffles 10 and cross-riffles 11. This plate forms a bed or receptacle upon which everything must fall and prevents gold and heavy material from falling out of reach of the active area of the suction-intake. The plate also acts as a plow, loosening the gravel as it advances, thus giving the pipe a better chance to raise the material. 55

Attached to the plate is a bail 12, from which a chain 13 extends upward around a roller 14 at the outer end of the crane and thence back to the scow or float. An operating-cable 15 extends from the lower end of 60 the boom 4 to a capstan 16 on the float. By means of the chain 13 and the cable 15 it is obvious that the parts may be moved to cause the plate or plow to dig into the bank of gravel and sand. 70

While I have shown the plate as substantially ovate in contour and provided with riffles, it is to be understood that the plate may be otherwise shaped and the riffles omitted without departing from the spirit of my 75 invention, the main object of the plate being, as heretofore stated, to resist or prevent the falling of gold to a point too remote from the inlet end of the suction-tube. The riffles, however, may be found of service under certain conditions, such as when there is a considerable current they will catch and hold the gold. 80

As indicated in Fig. 3, the arrangement of the suction-tube 5 may be changed—that is, 85 the boom 17 may be made in the form of a tube the inlet end of which will be secured sufficiently above the collecting-plate and the upper end placed in connection with the suction-pump. 90

In this invention the plate 8 will practically save all of the gold in the gravel disturbed, because as the draft of the water is toward the suction all the time, and that is the line of least resistance, the gold can fall nowhere 95 else but on the plate.

Having thus described my invention, I claim as new and desire to secure by Letters Patent—

1. In a dredger, a suction-tube and a collecting-plate supported and spaced below the inlet of the tube, the plane of said plate be-

ing extended in all directions from the end of the tube and parallel therewith, substantially as specified.

2. In a gold-dredging machine, a suction-tube, a plate supported adjacent to the inlet of the tube, and riffles on said plate, substantially as specified.

3. In a gold-dredging machine, a suction-tube, and a collecting-plate supported adjacent to the inlet of the tube and spaced below the same, the said plate also by being projected forward and serving as a plow or digging device, substantially as specified.

4. In a gold-dredging machine, a scow or float, a crane having swinging connection therewith, a boom supported by the crane, a suction-pump on the scow or float, a suction-tube leading therefrom and having its lower

end connected to the boom, a plate connected to the lower end of the boom and spaced from the inlet of the suction-tube, and means for causing movements of the parts, substantially as specified.

5. In a gold-dredging machine, the combination with a suction-tube and a suction-pump, of a collecting-plate secured adjacent to the inlet end of the suction-tube, the said plate being of substantially ovate form, and riffles on said plate, substantially as specified.

In testimony whereof I have signed my name to this specification in the presence of two subscribing witnesses.

OMER F. BARNES.
